UNITED STATES PATENT OFFICE.

THEODORE LATCH, OF STATE CENTER, IOWA.

COIN-CONTROLLED LOCK.

Application filed August 24, 1925. Serial No. 52,248.

The present application is a continuation in part of my application filed May 28, 1924, Serial Number 716,445, allowed March 6, 1925.

5 This invention relates to coin detecting means for vending or dispensing machines, and its primary object is to provide means for preventing the entrance of counterfeit, undersized or oversized coins, and in fact 10 any token except the standard coin for which it is designed, from entering the dispensing machine.

A further object of this invention is to provide a coin detecting mechanism of the 15 class described in which extremely accurate measurement is obtained by causing the coin to pass between fluted rollers whereby the measurement is made from the bottom of the milling on the periphery of the coin.

20 A further object of this invention is to provide a coin detecting mechanism of the class described in which the coin is caused to pass between a stationary and a lever mounted roller in such manner that a severe crushing strain is applied which will crush 25 or break counterfeit or inferior coins and at the same time prevent their entrance to the dispensing machine.

A further object of this invention is to 30 provide a coin detecting mechanism of the class described in which means is provided for attracting and diverting coins of magnetic properties and preventing their entrance to the machine.

35 A further object is to provide a mechanism of this character in which means is provided for returning to the operator any coin, either counterfeit or genuine, which the mechanism may chance to reject, with 40 the exception of magnetic coins, which are retained.

A further object of this invention is to 45 provide a coin measuring space consisting of a stationary member and a member mounted on a lever in such manner that the radius of a coin passing between said members is magnified at the long arm of the lever, which is employed to resist passage of the coin through said space if said coin is not of proper size and material to be accepted.

A further object is to provide coin measuring mechanism combining accuracy of measurement with arrangement whereby the diameter of the coin is magnified at the long

55 arm of a lever adapted to engage a large wearing face on a stop block in case the coin is not accepted, thus preventing failure of the rejecting means through wear of minute engaging parts.

A further object is to provide a mechanism which is reliable and sure to dispense the commodity when a coin of proper size and material is deposited and passes the coin measuring space.

60 A further object is to provide a mechanism in which locking means is provided for locking the dispensing devices in dispensing position until such time as the coin detecting parts have been again neutralized or centralized.

65 A further object is to provide a coin detecting means in which a cam stop block is employed for engagement by a cam lever to crowd the latter into a tensional measuring position relative to a coin, and thereafter the coin itself is employed as a cam to continue the action whereby the stop block and lever are caused to interengage and permit the dispensing devices to move to dispensing position.

70 Still a further object is to provide a mechanism of this class which is self cleaning, or in other words cannot be clogged or stopped by inferior coins or coins which are not readily accepted by the mechanism.

75 Another object is to provide such a mechanism in which a coin cannot be accepted until the machine is in proper condition for dispensing or vending.

80 Still another object is to provide coin controlled locks for the vending machines adapted for operation by one or more different standard coins for dispensing different amounts, and which will remain in locking position until the proper coin has been 85 inserted in the proper chute for the amount to be dispensed, and passed between the rollers provided for it.

85 A further object of this invention is to provide a mechanism of the character described 90 which is of relatively simple and inexpensive construction.

95 With these and other objects in view, my invention consists in the construction, arrangement and combination of elements 100 hereinafter set forth, pointed out in the claims and illustrated by the accompanying 105 drawing, in which—

Figure 1 is a front elevation illustrating my improved mechanism in position for practical use.

Figure 2 is a vertical section through the mechanism, on the line 2—2 of Figure 1.

Figure 3 is a rear elevation of the mechanism, taken interiorly of the machine, a portion of which is shown in section.

Figure 4 is a sectional elevation of the mechanism on the line 4—4 of Figure 2, and Figure 5 is a similar view on the line 5—5 of Figure 2.

Figure 6 is an enlarged detail view of a portion of the mechanism shown in Figure 4, particularly the coin carriers, the notched stop blocks and the strain producing levers.

Figure 7 is a horizontal section of the mechanism taken on the line 7—7 of Figure 3.

Figures 8, 9 and 10 are detail views of portions of the mechanism, particularly the coin carriers and notched stop blocks, with means for adjusting the same, Figure 8 being a rear elevation, Figure 9 a plan view, and Figure 10 a front elevation of these members.

Figure 11 is a view, principally diagrammatic, illustrating how a coin passes through the space between fluted rollers and is measured thereby.

My coin control mechanism and coin detecting devices may be used in connection with any desired and suitable form of dispensing or vending machine, for instance for the dispensing of liquids such as gasoline; and it is here shown and described as adapted for the reception of two different standard coins, such as the silver dollar and half dollar, for delivering one or another amount or quantity of the liquid. It is to be understood that this arrangement may be varied, however, not only as to the kind of commodity dispensed but also the range of selection of quantity, and the size and character of coin to be used in its operation.

A portion of the frame of the dispensing machine is shown and designated by the character A, and such frame is formed with an opening to receive the main supporting plate 12 of my mechanism, which may be referred to as a door for the compartment of the machine to which said opening gives access.

In the present instance certain mechanism of the dispensing machine is adapted to be operated, or its operation set in motion, by means of a shaft 13 which extends through the door 12 and has a crank handle 14 on its outer or forward end for manual operation; but it is to be understood that any other suitable means may be provided for this purpose, such for instance as a movable member of an electric switch or the like. In any event there is a connection between my coin control locking means and the shaft 13

or similar member whereby such member cannot be operated until the detecting mechanism has been returned to neutral position.

The means for holding the door 12 in the frame A includes projecting lugs 15 on said door adapted to engage behind said frame at the margins of the opening therein, together with any desired means for preventing unauthorized removal of the door. I have

here shown the door 12 formed with a chute 16 for one size of standard coin, such as the silver dollar, and also with a chute 17 for

another size coin, such as the fifty cent piece. The chutes 16 and 17 lead downwardly and toward the median line of the door from opposite points near the upper corners thereof, and open at their lower ends to the rear face of said door.

Suitable receiving means may be provided within the frame of the machine, or in connection with the interior of the door, for the acceptable coins; and an outer receptacle 18 is also provided, accessible from the outside of the door and having communication with the interior of the mechanism, for receiving the rejected coins and permitting their re-acquisition by the depositor.

A plate 19 is arranged parallel with, and spaced to the rear of the door 12 and carried thereby, and said plate serves to support some of the mechanism. A magnet

20 is supported centrally of the rear of the door 12 adjacent and between the inner ends of the chutes 16 and 17, and is adapted to attract and temporarily retain any magnetic coins which may be inserted in the chutes

and prevent them from passing to the dispensing machine or effect its operation.

A spindle 21 is journaled for rotary oscillation in the door 12 and plate 19, projects forwardly of said door and has a double handle 22 attached to its forward end, by means of which it may be manually rocked in either direction.

A substantially vertical lever 23 is fixed to the spindle 21 just rearwardly of the door 12, and its upper end is provided with a forwardly projecting pin

24 extending within and adapted for travel in an arcuate groove 25 formed in the rear face of the door. The upper end portion of the lever 23 projects past the magnet 20, and

when the spindle 21 is rocked as hereinafter set forth, said lever in its travel knocks off any magnetic coin which may be clinging to said magnet.

Pointed lugs 26 and 27 are formed on or fixed to the rear face of the door, near the inner ends of the respective chutes, with their points arranged inwardly; and said lugs are also beveled rearwardly from the door.

It is the function of the lugs 26 and 27 to deflect rearwardly from the door, and from their natural position in falling, any coins which are released from the magnet, so that they will not attempt to enter the coin carriers or otherwise impede the detecting mechanism.

When magnetic

coins are so attracted, released and deflected rearwardly, they fall into a portion of the machine to the rear of the door and are there retained.

5 The outer receptacle 18 is formed with a portion which is located partly inside or to the rear of the door 12, which door is formed with an opening or openings 28 furnishing communication between such interior portion and the outer portion of the receptacle; and such inner portion includes a rear wall 29 extending upwardly past said opening 28, parallel with and spaced rearwardly from the door, and side walls 30, 31 connecting 10 said rear wall with the door, said receptacle being open at its top both inside and outside the door. The upwardly projecting lever 23 is located against the rear face of the door and partly between said door and the rear wall 29 of the receptacle. A detent 32 is fixed to the spindle 21 immediately behind the rear wall 29, as by a pin 33, said detent extending downwardly toward and intersecting the operating shaft 13. The detent 32 is wide at its lower end, which is formed on a convex arc and has a notch 34 in its center to receive the shaft 13. The shaft in turn is formed with an upwardly opening notch 35 which is flat 20 and plane at its bottom, to receive the detent 32 at times. It is apparent that because of this interlocking arrangement, the shaft 13 cannot be operated unless the detent 32 is in its normal central position as shown, with its notch 34 axially of the shaft; and that the detent, and members connected therewith, can only be oscillated when the shaft is in the position shown, with its notch 35 opening directly upwardly, which is the 25 normal position said shaft will take, with the handle 14 depending downwardly as induced by gravity. A stem 36 is formed on and projects upwardly from the hub of the detent 32 and is formed on its lateral sides 30 with concaved seats engaged by the inner ends of opposed spring-pressed plungers 37 and 38 carried by brackets 39 and 40 respectively, which are adjustably mounted on the rear face of the plate 19 by means of screws 41 and 50 extending through slots 42 in said brackets and seated in said plate. The plungers 37 and 38 are arranged for reciprocation in apertured ears 43 projecting rearwardly from the brackets, and are urged 35 inwardly into engagement with the stem 36 by means of springs 44 and 45 coiled on said plungers and engaging one of the ears on the bracket and a pin 46 extending through the plunger. It is the function of the 40 spring-pressed plungers 37 and 38 to hold the detent 32, and parts connected therewith, in neutral position as shown, and to tend to return them to such position when moved therefrom.

65 Plates 47 and 48 are arranged transverse-

ly, one above the other, and spaced somewhat to the rear of the door 12, to which they are secured by screws 49 and 50. A carrier bar 51 is arranged for transverse reciprocation against the rear face of the door 12 and between adjacent margins of the plates 47 and 48, and said bar is formed with rearwardly projecting lugs 52 and 53 at its ends. Formed on the forward side of the carrier bar 51 and adjacent its respective 70 ends are coin carriers 54 and 55, each including a vertical slot extending therethrough on a curve as shown in Figures 5 and 10. The coin carriers 54 and 55 are adapted to receive coins from the chutes 16 and 17 respectively and carry them laterally for engagement with measuring and testing rollers to be described. Locking blocks 56 and 57 are mounted on the rear face of the carrier bar 51 and each is held in place by a single 80 cap screw 58. The locking blocks 56 and 57 are formed on their inner faces with a recess 59 of substantially rectangular form, opening to their inner faces. Mounted on the rear faces of the plates 47 and 48 respectively, and pivoted thereto at their outer ends by screws 60, are measuring levers 61 and 62, which are movable in a plane parallel with said plates. The levers 61 and 62 are forked at their inner ends, one arm 63 of each fork 85 being longer than the other and being directed toward and adapted to enter and fit closely in a recess 59 of a cam stop block 57 or 56 respectively. The levers 61 and 62 are oppositely arranged as shown, the short arms 90 of the forks thereof are offset rearwardly and are connected by a tension spring 64. A measuring and testing roller is mounted in fixed position on each side of the center of the device, the roller 65 being 100 carried between the door 12 and one end portion of the plate 48, while the other roller 66 is carried between said door and the opposite end of the plate 47. Similar rollers are movably carried by the measuring 105 levers and adapted to cooperate with the rollers 65 and 66; a roller 67 being carried by the lever 61 in substantial vertical alignment with the roller 65 and above it, and a roller 68 being carried by the lever 62 in substantial vertical alignment with the roller 66 but below it. The rollers 67 and 68 are arranged between the door 12 and the plates 47 and 48 respectively, and are journaled on pins 69 carried by the respective levers and 110 movable in slots 70 formed in said plates, which are behind the levers. The rollers 65, 66, 67 and 68 are knurled or fluted on parallel lines to form peripheral teeth as clearly shown in Figure 11, and it is their function 120 to very accurately measure and test any coins which pass or attempt to pass between them in the carriers 54, 55.

The operation of this part of the mechanism is as follows: A coin is inserted in one 125

of the chutes, such as 17 and falls by gravity along the rear face of the door 12, between the lever 23 and the uppermost measuring roller on that side of the device 5 namely 66; it being presumed that all the parts are in their neutral or centralized position; said coin entering the carrier 55 and being prevented from passing therethrough by the lower roller 68, it being noted that 10 the slot in the carrier curves outwardly. The operator then exerts pressure manually on one side of the double handle 22, to rock it toward that side of the device in which the coin has been inserted, thus oscillating 15 the spindle 21 and lever 23, as well as the detent 32. The lever 23 is formed between its ends with a lateral enlargement 71 or double cam located between and in the same plane as the coin carriers 54 and 55, and 20 when the lever is oscillated this cam portion exerts pressure laterally on one or the other of said carriers and tends to cause the bar 51 to move in its guides and carry with it the stop blocks 56 and 57. The coin, such 25 as 72, which has been inserted as above described, is carried laterally by the carrier 55 and attempts to pass between the rollers 66 and 68. It will be noted that this lateral movement also causes the stop block 56 to 30 approach the forked end of the measuring lever 62, and before the coin can pass between the rollers, the long arm 63 of the fork engages said stop block. The long arms 63 of the forked levers are formed on 35 their opposed faces with cams 73 adapted to be engaged by cams 73' formed on the stop blocks 56, 57 in their travel, such engagement causing the forked end of the lever 61 to be oscillated upwardly or the forked end 40 of the lever 62 to be oscillated downwardly, as the case may be. It will be appreciated that on account of the fact that the forked ends of the levers 61 and 62 are connected by the spring 64, movement of the one will 45 be communicated to the other, or if resisted greater tension will be placed in the spring. The arrangement and spacing of the rollers 65-67 and 66-68, and also the adjustment of the stop blocks 56, 57, is such that 50 when the proper coin for which either set of rollers is designed is carried toward such set of rollers, it will be measured thereby and passed between them. The measurement is accomplished from the bottom of the 55 peripheral milling on the coin, by the teeth produced by the fluting on the rollers, and is thus very accurate regardless of the amount of superficial wear to which the coin may have been subjected theretofore. When 60 the proper coin is thus passed between the rollers it applies just enough pressure on the lever-carried roller, such as 67 or 68, to deflect the lever enough from the movement generated by the other lever through 65 engagement of the stop block with its cam 73,

that the fork of said lever will be in alignment with the recess 59 of the stop block which is being moved toward it. This permits the long arm 63 of the lever to enter the recess and permits full movement of the 70 carrier bar 51 laterally. Otherwise the end of the long arm engages the face of the stop block, before the coin has passed between the rollers, and further movement is prevented. 75

To continue more specifically, lateral movement of the carrier bar as previously described carries the coin 72 to a position between the rollers 66 and 68 as shown in Figure 5, and assuming that such coin is the standard coin for which that side of the machine is designed, it is permitted to pass between them, by a rolling contact with said rollers and the accurate measuring herein-before described. Before the coin has 80 reached the measuring point, however, the cam stop block 56 has engaged the cam 73 of the lever 61 and raised it, thus pulling up on the inner end of the lever 62 through the spring 64. As the movement continues, the entrance of the coin to the space between the rollers 66 and 68 counteracts this upward pull to some extent, placing the lever under tension of the spring 64, and when the parts are properly adjusted the long arm of the lever 62 is placed in exact alignment with the recess 59 of the advancing stop block 56, and the movement thereof is not checked. This permits the carrier bar 51 to be advanced its complete amount of 85 travel through continued pressure on the handle 22, the coin is passed between the rollers and permitted to drop to the place provided for acceptable coins. 90

In the event the coin inserted is not the proper denomination, or is a counterfeit, it will not pass between the rollers, for one of several reasons: If it is either too large or too small in diameter, the accuracy of measurement applied by the rollers will produce the result of moving the lever 62 either too far or not far enough, and the forked end will not enter the recess 59 but will engage the face of the stop block and prevent its further movement and that of the carrier bar and coin. A similar result occurs in case the coin is of inferior material so that the fluted rollers bite into it or cause a crushing or breaking through the considerable strain which is applied. In any event, the movement cannot continue to the end of travel, and when the member 23 is returned to normal or neutral position, the coin will be carried back to its original position when inserted and will be supported by the lowermost roller, such as 68. The operator upon observing that the machine is stopped will naturally oscillate or jerk the handle 22 and cause the member 23 to be moved to the left of its neutral position as viewed in 100 105 110 115 120 125 130

Figures 5 and 6; and when any reverse pressure is applied an extractor lug 74 at the outer end of the carrier, in this instance 55, exerts back pressure against the coin 5 therein, causing it to fall on the inner side of the roller 68 and into the receptacle 18, whence it may be reclaimed by the depositor.

Any suitable means may be provided for 10 effecting the dispensing or vending by and through the complete travel of the carrier and parts connected therewith upon passage of an acceptable coin. In this instance I have shown a cross-head 75 fixed to the rear 15 end of the spindle 21, and links 76, 77, or other suitable connecting means, may be attached to the opposite ends of said cross-head and extend to the desired location for 20 connection and operation of the dispensing devices. In the event the commodity to be dispensed is a liquid such as gasoline, the links 76, 77 may be attached to suitable valves by which the liquid is dispensed, the 25 links and valves being operated only when the crosshead is oscillated to its extreme position in either direction by complete movement of the double handle 22 and spindle after acceptance of a coin.

I have also shown a rod 78 arranged transversely of the rear portion of the plate 19 and held in place in ears 79 and 80 formed thereon. An arm 81 is fixed to the spindle, extends upwardly and has its upper end forked and engaging the rod 78 freely. Tension springs 82 and 83 are coiled on the rod 78 on opposite sides of the forked arm, engaging at their outer ends the ears 79 and 80 and at their inner ends stops 84 on said pin. It is the function of the springs 82 and 83 to tend to centralize the spindle 21 and members connected with it, and to return them to central or neutral position after they have been moved therefrom. These springs may be used to supplement the spring-pressed plungers 37 and 38, or they may be used in lieu thereof.

Extending across the forward face of the door 12 and journaled for oscillation in bearings 85 and 86 carried thereby, is a neutralizing shaft 87 having a crank 88 at one end, which may be formed with an eye 89 on its end. A projection 90 is formed on and extends upwardly from the central part of the double handle 22. A latch 91 is pivoted at its lower end on the lower portion of the projection 90 and on its rear face, by means of a pin or bolt 92. The latch is arranged for sliding engagement with a segment 93 formed on the face of the door 12 and is pressed into engagement therewith by a spring 94 mounted in a recess 95 in the upper end of the projection 90. The segment 93 is formed with notches 96 and 97 near its ends, into which the latch 91 is pressed by the spring 95 when the spin-

dle 21 has been moved to the end of its throw upon passage of an acceptable coin; and this latching arrangement is provided in order to hold the cross-head 75, connecting members 76 and 77 and dispensing devices in open position until the dispensing operation has been completed. After such completion the parts are returned to neutral position by manual pressure on the crank 88 of the neutralizing shaft 87, or in any other 75 suitable manner. The oscillation of the shaft 87 causes a downwardly extending arm 98 thereon to displace the latch 91 from either of the notches 96 or 97, whereupon the springs 82 and 83, plungers 37 and 38, 80 or other suitable means, act to return the parts to central or neutral position.

In the present embodiment of this invention, which is particularly adapted for controlling the dispensing of liquid such as 85 gasoline, the crank 14 and shaft 13 may be employed for raising the liquid from a storage tank to a dispensing tank located at the upper end of a pump standard in the common way. After the liquid is so raised 90 into position for dispensing, the coin is inserted and the machine operated as previously described, and then returned to neutral position by tripping the shaft 87, or in any desired manner; in this instance the eye 95 89 of the crank on shaft 87 may be employed to receive a hook on the gasoline hose (not shown), so that when the hose is replaced its weight will automatically trip the devices for neutralizing or centralizing 100 the spindle 21. Any suitable means may be provided for preventing insertion of a coin to the detecting mechanism prior to the operation of lifting the liquid to dispensing position, such means forming no part of the 105 present invention.

It is desirable to provide means for adjusting the positions of the stop blocks 56 and 57, or rather their inclination and that of the recesses 59. For this purpose I show 110 adjusting screws 99 and 100, one on each side of the axis of each block, which screws are threaded through the ears 52 and 53 and engage the outer ends of the stop blocks. For adjustment of the blocks the cap screws 115 58 are first loosened, one or the other of the set screws 99, 100 loosened and the other correspondingly tightened, and when the desired inclination is obtained to permit entrance of the forked levers to the recesses 120 of the blocks, the cap screws 58 are again tightened.

The pin 24 on upper end of lever 23 is employed to block the exit to a chute 16 or 17 and prevent a coin falling therefrom when the lever has been oscillated to that side of the machine for dispensing purposes; and if a coin is inserted in the opposite chute at such a time it will fall into the machine 125 but there being no coin carrier in position 130

to receive it, the coin will fall into the receptacle 18 and be accessible to the depositor. Returning of the coins which are not accepted, with exception of magnetic coins, 5 is one of the features of my device.

Another valuable feature is that the machine cannot become clogged by unacceptable coins, as means is provided for removing them from the mechanism and disposing of them. Attention should also be called 10 to the accuracy of measurement by the fluted rollers and the interengagement of measuring levers with recessed stop blocks; and also the crushing strain which is applied for 15 detecting inferior coins such as those of lead, or bakelite chips, this strain being applied through the lever advantage obtained by having the lever-mounted rollers carried near the fulcrums of the levers, and the 20 long arms extended therefrom for engagement with the stop blocks, which strain is not dependent upon the spring tension. All these features make my mechanism 25 thoroughly practicable and adapt it for a great variety of uses in connection with dispensing and vending machines of different types. The lever advantage of the lever mounted measuring roller is also employed, by magnifying the diameter of the 30 coin being measured, to provide that a large wearing surface on the cam stop block is engageable by the long arm of the lever, so that while extreme accuracy of measurement is provided, yet the mechanism is not dependent upon minute or very precise engaging 35 members to stop the action when an improper coin is inserted, which might otherwise, because of wear on such parts, cause a failure of the rejecting mechanism. In 40 other words this arrangement provides that a wide face of the stop block is engaged by the end of the lever when the coin is rejected.

It should be noted further that in the 45 cam action of the stop block and lever as described, the lever is first engaged by the cam stop block to crowd the lever into a tensional measuring position insuring accuracy of measurement of the coin; and that thereafter when it has been determined that 50 the coin may pass the measuring space, the coin itself is employed as a cam to continue the movement of the lever toward the recess of the stop block so that the dispensing operation may be fulfilled.

After a coin has been accepted and the 55 parts moved to dispensing position, they are locked in such position by engagement of the latch 91 with a notch 96 or 97 so that there can be no interference with a completion 60 of the dispensing operation, until such time as such operation is completed and the parts neutralized or returned to central position by the means described, or any other suitable means provided for that purpose.

I have shown all the coin detecting mechanism carried by the door and having convenient connections with the dispensing means, which makes my device unitary and easy to assemble and install. 70

I claim as my invention—

1. A coin detector of the class described comprising a coin carrier, a notched member thereon, means for actuating the carrier, a pivoted arm, a fluted roller thereon for engaging the coin carried by the carrier, a second fluted roller forming with the first roller a coin receiving space through which a coin is adapted to be passed by the carrier, said arm having a part for engaging the notch in the member when a proper sized coin is passed between the rollers, and spring means for holding the arm in its extreme position. 75

2. A coin detector of the class described comprising a supporting member having a coin chute therein, a coin carrier slidably mounted in the member for receiving the coins passing through the chute, a notched block on the carrier, a pivoted arm, a fluted roller thereon for engaging a coin, said arm having a part for entering the notch in the block when a proper sized coin is placed in the chute, a spring for holding the arm in a position where it will not enter the notch, a hand operated member, a lever connected therewith and connected with the carrier for reciprocating the same, operating means actuated by the hand member, and spring means for holding the parts in neutral position. 80

3. A coin detector of the class described comprising a supporting member having a coin chute therein, a coin carrier slidably mounted in the support for receiving the coins passing through the chute, a notched block on the carrier, a pivoted arm acting with the carrier, a fluted roller thereon for engaging a coin, said arm having a part for entering the notch in the block when a proper sized coin is placed in the chute, a spring for holding the arm in its inoperative position, a hand operated member, a lever connected therewith and adapted to engage the carrier for reciprocating the same, an operating member actuated by the hand operated member, spring means for holding the parts in neutral position, and a magnet adjacent the chute for holding magnetic coins, said lever adapted to knock the 90 coins from said magnet when oscillated. 100

4. A coin detector of the class described comprising a coin carrier, a notched member thereon, means for actuating the carrier, a pivoted arm, a fluted roller thereon for engaging the coin carried by the carrier, a second fluted roller forming with the first roller a coin receiving and measuring space through which a coin is adapted to pass with the carrier, said arm having a part for en- 110

gaging the notch in the member when a proper sized coin is passed between the rollers, the flutings on said rollers operating to measure a coin from the bottom of the peripheral milling thereon whereby extreme accuracy is assured.

5. A coin detector of the class described comprising a coin carrier, a notched member thereon, means for actuating the carrier, an 10 arm pivoted at one end and having means at its other end for engaging the notch in the member when a proper sized coin is received, a fluted roller carried by said arm near its pivot for engaging a coin carried by 15 the carrier, a second fluted roller mounted in stationary position and forming with the first roller a coin receiving and measuring space through which a coin is adapted to be passed in said carrier, the longer portion of 20 said arm employed for entering said notched block being designed to magnify differences of spacing between the stationary roller and the roller mounted on the short portion of said arm.

25 6. A coin detector of the class described comprising a coin carrier, a notched member thereon, means for actuating the carrier, a pivoted arm, a fluted roller thereon for engaging the coin carried by the carrier, a 30 second fluted roller forming with the first roller a coin receiving space through which a coin is adapted to be passed by the carrier, said arm having a part for engaging the notch in the member when a proper sized coin is passed between the rollers, said arm being formed with a cam portion adapted for engagement by a cam portion of the coin carrier in its travel to oscillate said arm toward the notch in said member.

40 7. A coin detector of the class described comprising a coin carrier, a notched cam member thereon, means for actuating the carrier, a pivoted arm, a fluted roller thereon for engaging a coin carried by the carrier, a 45 second fluted roller forming with the first roller a coin receiving space through which a coin is adapted to be passed by the carrier, said arm having a part for engaging the notch in the cam member when a proper sized coin is passed between the rollers, and means for adjusting the inclination of said cam member and its notch for engagement by said arm.

55 8. A coin detector of the class described comprising a coin carrier, a notched member thereon, means for actuating the carrier, a pivoted arm, a roller on said arm for engaging the coin carried by the carrier, a second roller forming with the first roller a coin receiving space within which a coin must exactly fit before it can be passed by the carrier, said arm having a part for engaging the notch in the member only when a proper sized coin is passed between the rollers, and said part adapted to engage and

stop the carrier unless a proper sized coin is carried therein, and means for returning an unacceptable coin to the depositor when it fails to pass through said coin receiving space.

9. A coin detector of the class comprising a coin carrier, a notched member thereon, means for actuating the carrier, a member adapted to be moved to dispensing position, a pivoted arm, a roller carried by the arm for engaging a coin carried by the carrier, a second roller forming with the first roller a coin-receiving space through which a coin is adapted to be passed by the carrier, said arm having a part for engaging a notch in the notched member when a proper sized coin is passed between the rollers, such engagement operating to prevent movement of the movable member to dispensing position. 70 together with means for locking said member in dispensing position when it has arrived, manually operated means for releasing said locking means, and spring means for returning the carrier and parts connected therewith to neutral position.

10. A coin detector of the class described comprising a supporting member having a coin chute therein, a coin carrier slidably mounted in the member for receiving coins passing through the chute, a notched cam 75 stop block on the carrier, a pivoted arm, a roller on said arm for engaging a coin, said arm having a part for entering the notch in the stop block when a proper sized coin is placed in the chute, a spring for holding the arm in a position where it will not enter the notch, a hand operated member, a lever connected therewith and adapted to engage the carrier for reciprocating the same, operating means actuated by the hand member, 80 and spring means for holding the parts in neutral position.

11. A coin detector of the class described comprising a coin carrier, a cam stop block formed with a recess mounted on the carrier, means for actuating the carrier, an arm pivoted at one end and having means at its other end for engaging the recess in the stop block when a proper sized coin is received, a roller carried by said arm near its pivot 95 for engaging a coin carried by the carrier, a second roller mounted in stationary position and forming with the first roller a coin receiving and measuring space through which a coin is adapted to be passed in the carrier, the longer portion of said arm employed to magnify the diameter of a coin in the measuring space to produce accuracy in measurement and also to provide a large 100 wear resisting space for engagement on said stop block when a coin is rejected.

12. A coin detector of the class described comprising a coin carrier, a stop block thereon formed with a recess, a means for actuating the carrier, a pivoted arm, a roller there- 105 110 115 120 125 130

on for engaging a coin carried by the carrier, a second roller forming with the first roller a coin receiving space through which a coin is adapted to be passed by the carrier, said 5 arm having a part for engaging the recess in the stop block when a proper sized coin is passed between the rollers, said arm being formed with a cam portion adapted for engagement of a cam portion of the stop block 10 for crowding the arm in a tensional measuring position.

13. A coin detector of the class described comprising a coin carrier, spaced stop blocks thereon each formed with a recess, means for actuating the carrier, a pair of pivoted arms, a spring adapted to connect said arms and hold them under tension, a roller pivoted on each arm and adapted for engagement with a coin carried by the carrier when moving in one direction, a second roller adapted to form with each of the first rollers a coin receiving space, each arm having a part for engaging a recess in one of the stop blocks when a proper sized coin is passed between 20 the corresponding pair of rollers, each arm being formed with a cam portion adapted for engagement by a cam portion of the opposite stop block for crowding the arm to a tensional measuring position, the coin in the 25 carrier when passing between the rollers being adapted to continue the cam action and movement of the arm to such position that it may engage the recess of the appropriate stop block.

14. A coin detector of the class described comprising a coin carrier, a supporting member having a coin chute, a notched member on the carrier, means for actuating the carrier, a pivoted arm, a roller on said arm for engaging a coin carried by the carrier, a second roller forming with the first roller a coin receiving space within which a coin 40 must fit before it can be passed by the carrier, said arm having a part for engagement

with the notch in the member only when a 45 proper sized coin is passed between the rollers, and said part adapted to engage and stop the carrier unless a proper sized coin is carried therein, said supporting member being formed with a receptacle adapted to receive a coin which is rejected by said measuring devices, said receptacle opening to the outside of the supporting member so that the coin may be regained by the person depositing it. 50 55

15. A coin detector of the class described comprising a coin carrier, a stop member thereon, means for actuating the carrier, a pivoted arm, a fluted roller carried by said arm for engaging a coin carried by the carrier, a second fluted roller forming with the first roller a coin receiving space through which a coin is adapted to be passed by the carrier, said stop member and pivoted arm having interengaging parts to permit a continued movement of the carrier when a proper sized coin is passed between the rollers, and spring means for holding the arm in its extreme position. 60 65

16. A coin detector of the class described comprising a coin carrier, a stop member thereon, means for actuating the carrier, a pivoted arm, a fluted roller carried by the arm for engaging a coin carried by the carrier, a second fluted roller forming with the first roller a coin receiving space through which a coin is adapted to be passed by the carrier, said stop member and pivoted arm having portions adapted to engage each 70 75 80 other and prevent further movement of the carrier unless a proper sized coin is passed between the rollers, and spring means for holding the arm in its extreme position.

Signed at State Center, in the county of Marshall and State of Iowa, this 11th day 85 of August, 1925.

THEODORE LATCH.
